(57) CLAIM

The ornamental design for a tire, as shown and described.

DESCRIPTION

FIG. 1 is a front perspective view of the tire showing my new design;

FIG. 2 is a front elevation view thereof;

FIG. 3 is an enlarged partial front view thereof;

FIG. 4 is a right side elevation view thereof;

FIG. 5 is a left side elevation view thereof; and,

FIG. 6 is a top elevation view thereof.

The broken lines in FIG. 2 are a demarcation of the portion of the design visible in the enlarged partial front view of FIG. 3 and forms no part of the claimed design.

1 Claim, 6 Drawing Sheets
